UNITED STATES PATENT OFFICE.

STEPHEN W. TENER, OF EAST CLEVELAND, OHIO.

SAFETY PLIERS.

Application filed September 11, 1920. Serial No. 409,544.

To all whom it may concern:

Be it known that I, STEPHEN W. TENER, a citizen of the United States, and resident of East Cleveland, in the county of 5 Cuyahoga and State of Ohio, have invented certain new and useful Improvements in Safety Pliers, of which the following is a specification.

This invention relates to cutting tools, 10 and more particularly to pliers used in cutting wire, and has for its particular object, the provision of such pliers having safety means for holding both ends of the wire that has been cut.

15 Another object is to provide pliers of this class that will be strong, durable, cheap to manufacture, and simple in construction.

Another object is to provide pliers of this class that will resemble and follow 20 the general design of the ordinary well known and accepted design of pliers in use.

Heretofore, the generally accepted design of pliers in use has consisted of two jaw members having a head portion and a reduced shank or handle portion, the two members being pivoted together so that the cutting edges of the heads will meet to cut the wire. This construction of plier is simple, cheap to manufacture, and very durable, but has proved to be faulty in that it allowed the cut ends of the wire to fly away from the plier with more or less force, which has many times resulted in serious injury to the operator or his fellow workmen.

35 The present construction of pliers provides means cooperating with the usual jaws for clamping or holding the severed ends of the wire, thus positively preventing the ends flying away and injuring the operator or 40 his fellow workmen.

In the drawings,

Figure 1 is a side elevation of a pliers having my invention applied thereto.

Figure 2 is a top plan thereof.

45 Figure 3 is a front elevation thereof.

Figure 4 is a side elevation similar to Figure 1, but showing a wire between the jaws in position to be cut.

Figure 5 is a front end elevation similar 50 to Figure 3 showing the wire between the jaws in position to be cut.

Referring particularly to the drawings, the letters A and B designate the two main or cutting jaw members of the pliers, which 55 are of duplicate construction.

The jaw members comprise a head 2 and

an integrally formed handle portion 3, the head portion 2 being offset below the horizontal axis of the handle portion to provide leverage and being provided with a 60 slightly beveled cutting face 4.

The jaw members have flat side faces and are pivotally secured together by a pivot pin 5 in such a manner that the inner edges of their cutting faces 4 will meet to cut 65 wire or the like.

A third jaw member C, comprising a head portion 6 and a spring shank portion 7, is mounted on the pivot pin 5, and has its head offset so as to fit around the head 2 70 of the jaw member B, and is provided with a flat clamping face 8 which underlies the face 4 of the jaw member B and cooperates therewith to clamp the cut end of the wire.

The spring shank portion 7 has its free 75 end securely fastened to the handle of the jaw member A by a rivet 10, and therefore, the jaw members A and C will move in unison.

In operation, when pressure is applied to 80 the handle portion 3 of the members A and B, the heads 2 will move toward each other and the head 6 of member C will move with the head 2 of member A until it clamps against the wire being cut. The head 2 85 of member A will then continue its movement until the wire is cut, while head 6 of member C is stationary, the continued movement of head 2 of member A being taken up in the spring shank of member C which 90 will bow or give sufficiently to allow the edges of the cutting faces 4 of heads 2 to meet.

An additional or fourth jaw member D is employed to co-operate with the jaw member A to hold the other end of the cut wire 95 not held by jaw members B and C.

The jaw member D is similar to jaw member C, and comprises a head portion 11 and a spring shank portion 12, and is mounted on the pivot pin 5 so as to abut the outside face of jaw member A. The head 11 is offset from the shank 12 so as to fit around the head 2 of member A, and is provided with a flat clamping face 14 which underlies 105 the face 4 of jaw member A and cooperates therewith to clamp the end of the wire opposite from the end held by members B and C.

The spring shank portion 12 has its free 110 end securely fastened to the handle of the jaw member B by a rivet 15, and therefore,

the jaw members B and D will move in unison.

The operation of the fourth jaw D is substantially the same as the jaw C. That is, 5 the clamping face 14 of the head 11 will move with the head 2 of member B until it clamps the wire to be cut against the head 2 of the jaw member A, where it will remain stationary while head 2 of member 10 B will continue to move until the edges of the cutting faces 4 meet and cut the wire. The continued movement of the head 2 of member B is taken up in the spring shank of member D, which will bow or give, sufficiently to allow the edges of the cutting 15 faces to meet.

It will thus be seen that I have provided a pliers having positive clamping means for clamping both ends of wire to be cut prior 20 to the cutting thereof, thereby positively preventing the springing away or flying of the cut ends.

I claim:—

1. Pliers for cutting wire and the like, 25 comprising in combination, a pair of cutting jaw members, each of said members having a head portion and a handle portion, said head portion being offset from the horizontal axis of the handle portion to 30 provide leverage and being provided with a beveled face, a pivot passing through said head portions to hold said jaw members together, a pair of clamping jaws mounted on said pivot, each of said last named jaws 35 having a head portion and a flexible spring shank portion, said shank portion being se-

cured intermediate the ends of the handle portion of one of said cutting jaws and movable therewith, and said head portion being substantially the same thickness throughout 40 its length, and being adapted to bear against the cutting face of the other cutting jaw, thereby holding the ends of the cut wire.

2. Pliers for cutting wire and the like, comprising in combination, a pair of cutting 45 jaw members, each of said members having a head portion and a handle portion, said head portion being offset from the horizontal axis of the handle portion to provide leverage and being provided with a beveled 50 cutting face, a pivot passing through said head portions to hold said jaw members together, a pair of clamping jaws mounted on said pivot, each of said last named jaws having a head portion and a flexible spring 55 shank portion, said head portion being of less thickness than the head portion of said cutting jaws, and said shank portion being secured intermediate the ends of the handle portion of one of said cutting jaws and 60 movable therewith, said head portion being substantially the same thickness throughout its length and being offset with relation to the longitudinal axis of the clamping jaw so as to fit around the head portion and bear 65 against the cutting face of the other cutting jaw, thereby holding the ends of the cut wire.

In testimony whereof, I have hereunto signed my name.

STEPHEN W. TENER.
